CLAIM

The ornamental design for a film applicator, as shown and described.

DESCRIPTION

FIG. 1 is a front, right and bottom perspective view of a film applicator, showing my new design;

FIG. 2 is a rear, left and top perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 a front, right and bottom perspective view of the film applicator in open status; and,

FIG. 10 a rear, left and top perspective view of the film applicator in open status.

The broken lines shown in the drawings illustrate portions of the film applicator that form no part of the claimed design.
